CLAIM

The ornamental design for a stick pump cordless, as shown and described.

DESCRIPTION

FIG. 1 is a front perspective view of a stick pump cordless, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the stick pump cordless in a state of use.

The broken lines in the drawings illustrate the portions of the stick pump cordless, which form no part of the claimed design. The stick pump cordless is shown with dash-dot line depicting a symbolic break in its length. The appearance of any portion of the article between the break lines forms no part of the claim design.
